UNITED STATES PATENT OFFICE.

MATTHEW MICHAEL KANE, OF MONTGOMERY, ALABAMA, ASSIGNOR OF ONE-HALF TO
WILLIAM J. GARDNER, OF MONTGOMERY, ALABAMA.

RAILWAY-SIGNAL.

No. 906,238.

Specification of Letters Patent.

Patented Dec. 8, 1908.

Application filed November 2, 1907. Serial No. 400,362.

To all whom it may concern:

Be it known that I, MATTHEW MICHAEL KANE, a citizen of the United States, and a resident of Montgomery, in the county of 5 Montgomery and State of Alabama, have invented a new and Improved Railway-Signal, of which the following is a full, clear, and exact description.

This invention relates to railway signals 10 such as used on signal systems for preventing collisions or accidents caused by open switches.

The object of the invention is to produce a signal or semaphore of improved construction adapted to be used with a system such as that suggested; more specifically the object is to construct a signal or semaphore in such a way that it may be readily operated so as to display different colors indicating 20 whether the track is clear or not.

A further object of the invention is to provide an improved signal.

The invention consists in the construction and combination of parts to be more fully 25 described hereinafter and particularly set forth in the claims.

Reference is to be had to the accompanying drawings forming a part of this specification, in which similar characters of reference 30 indicate corresponding parts in all the figures.

Figure 1 is a perspective showing the signal posts on opposite sides of the track, and showing how they are connected with the electric cable conduits; the lower portion of 35 this view shows the parts in cross section; Fig. 2 is a side elevation showing a track device by means of which the signals are operated; Fig. 3 is an enlarged side elevation of the middle portion of the track device shown 40 in Fig. 2, the cover plate being removed and certain parts being shown in section; Fig. 4 is a vertical cross section through the parts shown in Fig. 3; Fig. 5 is a front elevation of one of the signals, certain parts being broken 45 away and shown in section; Fig. 6 is a vertical section similar to Fig. 5, but showing the parts in a different relation; Fig. 7 is a horizontal section taken on the line 7—7 of Fig. 6; Fig. 7^a is a front elevation showing a 50 portion of the signal plate and illustrating its construction in detail; Fig. 7^b is a horizontal section on the line 7^b—7^b of Fig. 7^a, and further illustrating the construction; Fig. 8 is a vertical cross section through one of the 55 rails at a track device and near a switch

point, and indicates the manner in which the switch point controls the track device; this construction is adopted where the open or closed condition of the switch is indicated by the signal; Fig. 8^a is a side elevation of the 60 parts shown in Fig. 8; Fig. 9 is a diagrammatic view showing a short portion of a railway track having a turn-out or siding, and illustrates the arrangement for operating the 65 signals automatically from the siding to show whether there is a train on the siding or whether the switch at the end of the siding is open or closed; Fig. 10 is a diagrammatic view showing a short portion of the railway 70 track and indicates the wiring arrangement in connection with the signals which are maintained to indicate danger in advance and in the rear of the moving train; and Fig. 11 is a front elevation of one of the signals and showing the upper portion of a signal post. 75

Referring more particularly to the parts, and especially to Fig. 1, 1 represents the railroad track, at the side of which conduits 2 and 3 are arranged, running longitudinally of 80 the track. In these conduits electric cables 4 are carried, the conductors of which pass through lateral conduits 5 and 6 to the signal posts 7 and 8, said posts being arranged on opposite sides of the track and at intervals. 85 The signal posts 7 and 8 carry signals 9 respectively, which project in a horizontal position toward the track. The signal on the right of the track has its front toward the approaching train, while the signal on the left has its back toward the approaching train. In this way the signals on one side of the track will be used by trains passing in one direction, while those on the other side will be used by trains passing in the opposite 95 direction.

Referring now to Fig. 10, along the railway track 1 the signals 9 are disposed. I designate these signals collectively by the numeral 9, while the signals at the upper portion of the sheet are indicated by the numeral 9^a and those at the lower portion of the sheet by the numeral 9^b. The signals 9^a will be used by trains passing on the track from right to left, while the signals 9^b will be 100 used by trains passing in the opposite direction. In practice, these signals will be arranged about 110 yards apart, but they may be spaced a greater or less distance apart if desired. 105 110

In the conduit 3 main line wires 10 and 11 are laid, and at the same distance apart and intermediate of the signals as shown, I provide track devices 12, 13 and 14. In the 5 illustration I have shown only three of these track devices, this being sufficient for the purpose of illustrating the operation of the signals. The construction of the track devices is very clearly shown in Figs. 2 and 3. 10 Each track device is connected by conductors with the main line wires 10 and 11. It will be sufficient to trace out the circuit arrangement for one of the track devices and one pair of the signals. Referring to the 15 track device 12, this track device is connected through the wires 15 and 16 with the line wires 10 and 11 respectively. As will appear from the description to be made hereinafter of the track devices, when these track devices 20 are operated by the wheels of a passing train, the wires 15 and 16 are connected respectively with the wires 17 and 18. From these wires 17 and 18 six loops or branch circuits are formed which pass up and down 25 the track respectively. Those which pass in one direction on the track operate the signals on the right of the track in the direction in which the train is advancing, while those which pass in the opposite direction operate 30 the sections on the opposite side. In this way as the train passes a track device, signals are maintained in the "danger" position both in advance and in the rear. From the 35 wire 17 a wire 19 leads to a longitudinally disposed wire 20 which runs down the track and crosses by a cross wire 21 to the signal 9^a which lies almost opposite the track device; returning on the wire 22 from the signal connection, it is attached to a longitudinally disposed wire 23 from which another wire 24 40 leads back to and connects with the wire 18. In this way a complete circuit is closed to the nearest signal on the opposite side of the track. Similar circuits which are indicated 45 in the drawings, are closed through the signals 9^a which are disposed to the right of the one the wiring of which has just been described.

Referring to the track device 14, the 50 circuit through the signal in advance of the train will be described, it being understood that the train is passing from the right to the left as before. This track device is connected by wires 25 and 26 with the main line 55 wires 10 and 11 respectively, and when the track device is closed, these wires 25 and 26 are connected respectively with wires 27 and 28. When the circuit is closed, the current passes from the wire 28 to a longitudinally 60 extending wire 29 which runs forward along the track and passes out through one of the signals 9^b as indicated. From this signal the current returns on a wire 30 which connects with a longitudinally extending wire 31, 65 which runs back down the track and con-

ncts with a wire 32 which leads back to the wire 27. Similar circuits are provided for the six signals in advance of the train. From this arrangement, the wiring system will comprise a number of longitudinally disposed leader lines 33 which run along the track to operate the rear signals, and similar wires 34 which run along the track to operate the signals in advance. These wires 33 and 34 are laid in the conduit 2, while the 70 main or feed wires 10 and 11 run in the conduit 3.

The construction of one of the track devices will now be described, referring especially to Figs. 2 to 4 inclusive: Each track 80 device comprises a box 35 which is attached to the side of the rail as shown, and at one side of this box a plunger 36 is guided vertically, and this plunger passes up through the box to a point near the rail head 37, where 85 it is connected by a pivot bolt 38 with treadle levers 39. The outer ends of these levers are connected pivotally to braces or links 40 connected by pivot bolts 41 with the rail. The plunger 36 is held in an elevated position so 90 that the treadle lever 39 projects above the rail, by means of a helical spring 42 which is disposed under the plunger within the box 35, as shown in Fig. 3. Within the box I provide a suitably insulated double knife 95 switch 43 which is operated by means of a pin-and-slot connection 44 with the plunger. To the terminals of this switch, wires 45 and 46 lead from the main line, and these wires correspond to the wires 15 and 16 described 100 in connection with the track device 12. These wires 45 and 46 may be connected respectively with the wires 47 and 48 which lead from the other side of the switch, and these wires 47 and 48 correspond respectively 105 to the wires 17 and 18 of the track device 12. These wires 45 and 48 are carried out through a suitable conduit or tube 49 which passes through the bottom of the box. From this arrangement it should be understood that 110 when a train is passing a track device, the wheels press the treadle levers 39 and close the switch 43, closing the circuits in the manner described in connection with Fig. 10.

Referring now to Figs. 8, 8^a and 9, the arrangement for indicating whether a siding is 115 safe or not will now be described. Referring especially to Fig. 9, 50 represents the siding off from the main track 51. Along the main track I provide signals 52 which are operated 120 according to the system described above, by trains passing along the main track. In addition to this, they may be operated by track devices 53 which are disposed along the siding 50. The signals 52 which are disposed opposite to the siding, are up and down the track for a considerable distance, and are of the special type illustrated in Fig. 11; that is, each signal, in addition to its 125 lights or similar parts which are used in con-

nection with the main track signal system, is provided with a green light 54, and these green lights 54 are placed in loops or conductors 55 which are connected with lead wires 56 which extend longitudinally up and down the track. From the main line wires 57 and 58 wires 59 and 60 respectively extend over to each of the track devices 53, and when a track device is passed, these wires 59 and 60 are connected respectively with wires 61 and 62. The wire 61 is connected with the lead wire 56, while the wire 62 connects with the lead wire 63 which runs parallel with the lead wire 56. From this arrangement it will be understood that the signals 52 are placed in parallel arrangement so that when the track device is closed, a number of signals up and down the track will show green or any color desired. In addition to this, I provide an arrangement for indicating whether the switch 64 is open or closed. In the illustration, Fig. 9, I have shown the arrangement for indicating the condition of one of the switches for the siding. In practice, it should be understood that the switches at both ends of the siding will have similar circuit arrangements. For this purpose, near the switch I provide a track device 65, which is similar in construction to the track device already described, but it is arranged to be operated by the moving switch point 66 as illustrated in Figs. 8 and 8^a. In order to enable the movement of the switch point 66 to operate the signal, I provide a yoke 67 which engages one of the treadle levers 68, and this yoke is connected by a link or connecting rod 69 with an offset link 70, and this link is connected by means of a bell crank lever 71 with a link 72 which is attached to the flange of the switch point. From this arrangement, when the switch point moves over to open or close the switch, the track device will be operated so as to open or close the knife switch described above and illustrated in Figs. 3 and 4. The track device 65 is connected by means of a suitable circuit 73 with a signal 74 placed down the track from the end of the switch, or there may be if desired, a number of these signals of the type shown in Fig. 1, that is a main line signal. From this arrangement it should be understood that when the switch is open a red light will be presented at the switch signal.

As indicated in Fig. 1, the cable in conduit 3 is connected by an offset with each track device. Through each of these offsets the wire connections are made to the track devices. The wires 56 and 63 (Fig. 9) are run through the conduit 2.

The construction of the signal arms or signal devices will now be described, referring especially to Figs. 5, 6 and 7. Each of the signals consists of a horizontal case or arm 75, which is constructed water and weather proof, so that the interior thereof is fully pro-

tected, the forward side being provided with a pane of glass 76. On the inside of the rear wall of this case longitudinal ribs 77 are attached which afford support for a plurality of wings 78, the said wings being provided at one edge with gudgeons or pivots 79, which are rotatably mounted in the ribs, as shown. These wings are painted white on one side and red on the other, and they are adapted to lie folded against each other, as indicated in Figs. 6 and 7, or in a reversed position, as shown in Fig. 5. See also Fig. 7^b. The adjacent wings over-lap each other in these two positions, so that in one position they appear as a continuous white plate or signal (each wing constituting a section of the signal); thus the signal shows "safe", and in the other position the signal will show red indicating "danger". Near their pivots 79, the wings are formed with slots 80, respectively, across which vertical pins are passed, and to these pins the ends of links 81 are attached. The end link 82 near the pole is connected to an armature lever 83 co-operating with an electro-magnet 84, so that when the magnet is energized it will pull the lever over, as indicated in Fig. 6, to the "danger" position. The wings may be pulled over to the reversed position by a similar armature lever 85 at the other end of the case, controlled by an electro-magnet 86 and connected with the wings by the end link 87. At the inner end of the case 75 a switch 88 is provided, the contact terminals of which are connected with the magnet 86 through the conductors 89, and this switch is normally held closed by a spring 90, as shown. The switch is provided with an armature 92 co-operating with an electro-magnet 93. The magnets 84, 93 and the lights 91 are connected through the circuit wires 21 and 22, as indicated in Figs. 5 and 6, the lights and the magnets 84 being connected in parallel by conductors 84^a.

As indicated in Fig. 10, the conductors 21 and 22 lead from the track devices, so that the current is normally not on through these magnets. The switch 88 is connected by conductors 88^a, 88^b with the main circuit wires 10 and 11, so that the current is normally on through the magnet 86. When the track device corresponding to a certain signal is pressed down by a wheel of a passing train, the magnet 93 opens the switch 88, and the magnet 84 becomes energized. This magnet then pulls the signal wings into the "danger" position shown in Fig. 6, and the light 91 which was normally dark, now glows. To the lever 83, a spring 83^a is attached, which operates to pull the signal to "danger" position in case the electric current should fail; in this way the train men will be apprised of the disordered state of the signal system and will be put on their guard. As soon as the current fails, of course the spring 90 will close the switch 88 again; hence if the current

should fail, the spring 83^a will pull the signal over to "safe", but the light 91 will not be lit. The train man finding this condition will proceed with caution. The choice of the 5 colors for the signal wings is, of course, conventional, and other colors than red and white might be selected if desired.

The entire system, including the signals and conduits, is constructed absolutely weather 10 and waterproof, so that the reliability of the signals under all conditions, is assured. The current for the system will be supplied from power stations in the cities along the railway line.

15 Having thus described my invention, I claim as new and desire to secure by Letters Patent:

1. A signal having a plurality of reversible wings adapted to show different colors in different positions, means connecting said wings to move the same in unison, an armature lever connected with said wings, an electro-magnet controlling said armature lever and normally holding said wings in their 25 "safe" position, and means tending to pull said wings into the reverse or "danger" position, said means operating when the current is broken through said magnet.

2. A signal having a plurality of pivoted wings, said wings having openings therein, links connecting said wings and attached thereto in said openings, and means for pulling said links to hold said wings upon each other in one position and in a reversed position.

3. In a signal, in combination, a signal plate, an armature lever connected with said plate, an electro-magnet coöperating with said armature lever and affording means for holding said plate in a "safe" position, a second armature lever connected with said plate, a second electro-magnet coöperating with said second armature lever and tending to move said plate into the "danger" position,

45 tion, an electrically-controlled switch controlling said first electro-magnet, a circuit passing through said first electro-magnet and said switch, and a second circuit passing through said electrically-controlled switch and said second electro-magnet.

50

4. In a signal, in combination, a reversible signal plate, an armature lever connected therewith, an electro-magnet coöperating with said lever and tending to hold said plate in a "safe" position, a second armature lever attached to said plate, a second electro-magnet coöperating with said second lever and tending to move said plate into a "danger" position, a circuit passing through 55 said first electro-magnet, an electrically-controlled switch in said circuit, a second circuit passing through said electrically-controlled switch and said second electro-magnet, and a track device in said second circuit.

60

5. In a signal, in combination, a reversible signal plate, an armature lever connected therewith, an electro-magnet coöperating with said armature lever adapted to hold said signal plate in a "safe" position, a second armature lever connected with said plate, a second electro-magnet controlling said second lever and tending to hold said plate in a "danger" position, an electrically-controlled switch, a circuit passing through 65 said electrically-controlled switch and said first electro-magnet, a second circuit passing through said electrically-controlled switch and said second electro-magnet and having a branch including an electric light, and a spring tending to hold said switch in its 70 closed position.

75

In testimony whereof I have signed my name to this specification in the presence of two subscribing witnesses.

MATTHEW MICHAEL KANE.
